LOCK

Charles S. Preston, Houston, Tex.

Application October 25, 1932, Serial No. 639,410

5 Claims. (Cl. 292—189)

This invention relates to a lock.

An object of the invention is to provide a lock of the character described specially designed for use on window sashes and other sliding closures for securing the same either in partially open or in closed position.

The lock is specially adapted for use as a side lock on a vertically slideable window sash whereby the sash may be locked closed or maintained in selected open positions.

Another object is to provide a lock of the character described arranged to be maintained in active position by gravity and to be released manually and includes, also, means for securing said lock in either active or released position.

Another object is to provide a locking device of the character described which, while specially designed as a window sash lock, is also capable of general use.

With the above and other objects in view the invention has particular relation to certain novel features of construction, operation and arrangement of parts an example of which is given in this specification and illustrated in the accompanying drawing wherein:

Figure 1 shows a perspective elevational view of a preferred form of the lock showing the cover plate removed.

Figure 2 shows a perspective view of the bolt actuating weight employed.

Figure 3 shows a perspective view of the lock bolt.

Figure 4 shows a perspective view of the cover plate.

Figure 5 shows a fragmentary elevation of the facing strip employed.

Figure 6 shows a sectional view taken on the line 6—6 of Figure 1.

Figure 7 shows another type of the lock showing the cover plate removed.

Figure 8 shows a perspective view of said cover plate.

Figure 9 shows a perspective view of a keeper which may be employed.

Figure 10 shows a perspective view of the keeper nut.

Figure 11 shows a perspective view of the keeper plate, and

Figure 12 shows a sectional view of said keeper and keeper plate assembly.

Referring now more particularly to the drawing, wherein like numerals of reference designate similar parts in each of the figures, the numeral 1 designates a casing, preferably rectangular in form, which may be counter-sunk into a sash

or other closure as 2 and which has the over-turned end wings 3, 3. A cover plate 4 may be fitted over said casing and said cover plate and casing secured to the sash by means of suitable screws 5, 5 which are fitted through the cover plate and through the wings 3 and are screwed into the sash.

Slidably mounted in the casing 1 there is a weight 6, preferably rectangular in form and the lower end of this weight has the diagonal slot 7 cut therein. Across the lower end of the casing there is a bolt 8 which is slidably mounted and whose free end is adapted to be projected through the side opening 9 of the casing 1. The bolt 8 has a tenon 10 secured thereto and preferably formed integrally therewith and which has a sliding fit in the diagonal slot 7.

When the weight 6 is moved upwardly in the casing, the coaction of one side of the slot 7 with the corresponding side of tenon 10 will cause the bolt 8 to be retracted and when the weight 6 is lowered, the coaction of the other side of the slot 7 with the tenon 10 will cause the bolt 8 to be projected into active position. Said bolt 8, it is to be noted, has a shoulder 11 engageable against the side of the casing 1 to limit the outward movement of the bolt.

The cover plate 4 has a vertical slot 12 and there is a thumb screw 13 whose shank projects through said slot and has a threaded connection 85 with the weight 6. The weight may be elevated by said thumb screw and lowered by gravity and the bolt 8 may be locked in active or retracted position by screwing said thumb screw inwardly until the friction face 14 thereof is brought into 90 secure frictional engagement with the cover plate 4.

When this lock is used on a slideable closure such as a window, a keeper plate such as 15 may be secured to the adjacent facing. This keeper plate may be provided with the suitable spaced openings 16 into which the bolt 8 may be projected to lock the sash or other closure in the desired position, that is, closed or partly, or entirely open.

In the form shown in Figure 7 the numeral 17 designates a casing having the end wings 18, 18. This casing may be countersunk into the sash or other closure and its cover plate 19 fitted there-over and secured in place by means of screws 105 which pass through the openings 20, 21 and are screwed into the sash underneath as explained in connection with Figure 6. In the casing 17 there is a weight 22 preferably rectangular in form which may have an oblong slot 23 therein. 110

The cover plate 19 has an opening 24 to permit access to said weight whereby the weight may be lifted or permitted to drop. In this form of the lock the weight 22 has the upwardly converging diagonal slots 24, 24, and beneath the weight there are the oppositely arranged transversely movable bolts 25, 25, which have the respective tenons 26, 26 preferably formed integrally therewith which work in said slots 24, 24. The lower margin of the casing 17 has a centrally located transverse slot 27 and opposite this slot the weight 22 has a deep transverse slot 28. The inner ends of the bolts 25 are upwardly beveled as at 29, 29.

This type of lock, illustrated in Figure 7, may ordinarily be attached to the lower margin of the window sash and upstanding from the casing beneath there is a keeper 30. This keeper has a shank 31 which is threaded into a nut 32, seated in the casing 33 beneath. Counter sunk into the upper face of the casing 33 there is a keeper plate 34 which has a transverse slot 35 to receive the keeper 30 as shown in Figure 12 and the keeper plate is attached to said casing 33 by means of screws 36 and rests against the upper end of the nut 32 whereby the keeper 30 is secured in place. The keeper 30 has the opening 37 to receive the inner ends of the bolts 25.

The keeper 30 is so located that when the window sash is closed said keeper will pass through the slot 27 and will force the bolt 25 apart and will enter the slot 28 and when in said last mentioned position the inner ends of the bolts 25 will align with the keeper opening 37 and the weight 22 will by gravity act to force said bolts 25 into the opening 37 of the keeper whereby the sash, or other closure will be locked in closed position. When it is desired to release the lock, the weight 23 may be manually elevated and this will operate, through the tenons 26, to release the bolts 25 from the keeper 30 whereupon the window may be opened.

The drawing and description disclose what are now considered to be preferred forms of the invention by way of illustration only while the

broad principle of the invention will be defined by the appended claims.

What I claim is:

1. A lock comprising a casing, a weight therein having an oblique mortise forming a bearing, a laterally movable lock bolt in the casing lying in a common plane with the weight and having a tenon which conforms in shape to and fits in said bearing, and means accessible outside of the casing for lifting said weight whereby said bolt may be withdrawn into inactive position. 80

2. A lock comprising a casing, a flat, plate-like weight therein having an oblique mortise forming a bearing, a laterally movable lock bolt in the casing aligned with the weight and having a tenon which works in said bearing, means for moving said weight to actuate said bolt and means for securing said weight in fixed position. 85

3. A lock comprising a casing, a weight therein having oblique bearings, oppositely arranged lock bolts in said casing, tenons on said bolts which work in said bearings, said casing having a keeper-receiving slot between said bolts. 90

4. A lock comprising a casing having a keeper-receiving slot, a weight in the casing having oblique bearings, oppositely arranged lock bolts in the casing lying in a common plane with the weight, one on each side of said slot, tenons on said bolts which fit closely in said bearings, said tenons and bearings forming means whereby the bolts may be projected into active position into said slot or into retracted position in accordance with the movement of said weight. 100

5. A lock comprising a casing, a flat relatively thin weight slidably mounted in the casing and having an oblique mortise, provided with parallel bearing faces, a lock bolt mounted to slide transversely relative to the weight and having a tenon which fits closely in said mortise and has parallel bearing faces arranged to work against the bearing faces of the mortise, said lock bolt and tenon lying in a common plane with the weight. 110
